UNITED STATES PATENT OFFICE.

ECKARDT V. ESKESSEN, OF NEW YORK, N. Y.

MOLD FOR DUMMY AERIAL BOMBS.

1,296,639.

Specification of Letters Patent. Patented Mar. 11, 1919.

Application filed August 8, 1918. Serial No. 248,967.

To all whom it may concern:

Be it known that I, ECKARDT V. ESKESSEN, a citizen of the United States, and a resident of New York, in the county of New York and State of New York, have invented certain new and useful Improvements in Molds for Dummy Aerial Bombs, of which the following is a specification.

My present invention relates generally to molds for plastic material, and more particularly to a mold for forming dummy aerial bombs of terra cotta, the clay for which may be dumped in measured or weighed quantity within the mold and by means of pressure forced readily and quickly to the desired shape without the difficulties and delays incident to known apparatus for this purpose.

The primary object of my invention is therefore the provision of a quick acting effective apparatus for this purpose as well as one which will be inexpensive in its nature and strong and durable in use.

In the accompanying drawings illustrating my present invention,

Figure 1 is a vertical longitudinal section through a mold constructed in accordance with my invention under maximum pressure,

Fig. 2 is a horizontal section taken longitudinally through the mold,

Fig. 3 is a vertical longitudinal section with both of the mold parts elevated,

Fig. 4 is a vertical transverse section with the parts in the position shown in Fig. 1, and

Fig. 5 is a similar view with the parts shown in the position of Fig. 3.

Fig. 6 shows a somewhat different construction.

Referring now to these figures, my invention proposes a mold including a rectangular mold case 10, the side walls 11 of which have a series of openings 12 opposite one another and adjacent to one end, for the reception of pins or plungers 13. The mold case 10 also has its end walls 14 provided with openings 15 for the reception of a rod or stem 16, the opposite ends of which project beyond the end walls 14 and one end of which may have a handle 17 for convenience in the insertion of the rod or stem within, and its removal from, the mold case.

The mold itself is in two sections, a lower section 18, and an upper section 19, each of an external shape and size to slidably

interfit the interior of the mold case 10, and each provided at its ends with recesses 20 which, when together, form openings opposite the openings 15 of the mold case end 60 walls 14 so that the rod or stem 16 may extend axially through the mold space formed by the opposing cavities 21 of the two mold sections cut within their adjacent faces, and when together forming a contour or outline of the article to be molded.

Both of the mold sections 18 and 19 have projecting lugs 22 therein adjacent the smaller end of the mold space or cavity and have their side edges recessed as at 23, the 70 recesses when together forming openings opposite the openings 12 of the mold case side walls 11 so as to permit the pins or plungers 13 to project at their inner ends into the mold space or cavity as seen in Fig. 2. 75

The lower mold section 18, which is supported upon any suitable surface forming the base of the mold case, is elevated at the end of each molding operation by means of an elevating plunger 24 engaging its lower 80 surface at a point substantially midway between its ends and the upper mold section 19 is both lowered and raised by a power screw 25 which engages its upper surface substantially midway between its ends and 85 which in practice is connected to any suitable source of power for forcing the upper mold section downwardly to the required pressure and elevating the same after such pressure has been released and the clay is 90 forced to completely fill the mold cavity.

The pins or plungers 13 are pivotally connected at their outer ends at 26 to intermediate points of side levers 27 in turn pivotally connected at one end as at 28 to lugs 95 29 projecting from the sides 11 of the mold case and having handles 30 at their opposite ends.

In operation, the plunger 24 is lowered to permit the lower mold section 18 to be seated downwardly within the mold case 10 and when so seated it is obvious that the rod or stem 16 may be thrust through the end wall openings 15 of the lower case, across the upper portion of the lower mold section 105 18. The levers 27 may at the same time be moved inwardly so as to thrust the pins or plungers 13 into the position shown in Fig. 2, after which the desired quantity of clay or other suitable plastic material is placed 110 within the lower mold section and the upper mold section 19 is lowered until the maxi-

mum pressure is reached against the lower section. This pressure serves to force the clay or other plastic material to completely fill the mold space as desired, and subsequent to release of the pressure the upper section 19 may be elevated and, after the rod or stem 16 has been withdrawn longitudinally through the mold form and the levers 27 moved outwardly to withdraw the pins or plungers 13, the lower mold section 18 may be elevated by the elevating plunger 24 so as to raise the molded article to a point level with or higher than the walls of the mold case 10. Any suitable bar or like implement may then be passed through the core or axial opening of the molded form from which the rod has been withdrawn, so that the article may be readily lifted from the lower mold section 18 and carried to a drying space where, if of terra cotta clay, it is permitted to cure before drying.

While my invention has been described, and is particularly applicable to the formation of dummy aerial bombs, it is obvious that it may be utilized for other articles, and that it will be strong and durable in use as well as calculated to bring about speed and effective results.

Instead of making the opening 15 as shown in Fig. 3 for the reception of the rod 16, such opening may be a slot extending to the upper end of the end plate 14, as shown in Fig. 6 of the drawing.

I claim:

1. A mold of the character described comprising superposed mold sections forming a

mold cavity therebetween and having recessed side and end portions, forming side and end openings, a mold case in which the said mold sections are movable vertically, having side and end openings to register with the side and end openings of the mold sections, a rod for insertion longitudinally within the mold cavity through the end openings, and transverse plungers shiftable in the side openings, as described. 40 45

2. A mold of the character described comprising superposed mold sections forming a mold cavity therebetween and having recessed side and end portions, forming side and end openings, a mold case in which the said mold sections are movable vertically, having side and end openings to register with the side and end openings of the mold sections, plungers in the side openings, a rod for insertion longitudinally within the mold cavity through the end openings, and levers pivoted at the sides of the mold case and to which the said plungers are connected, as 50 55 60 described.

3. A mold of the character described comprising superposed mold sections forming a mold cavity therebetween, and having recessed end portions forming, when together, end openings, a mold case in which the said mold sections are movable vertically, having openings in its end walls arranged to register with the end openings of the mold sections, and a core rod movable 70 within and from the mold cavity through the said end openings of the case and mold sections, as described. 65

ECKARDT V. ESKESSEN.
